MOVING STAIRWAY

Edgar M. Bouton, Chicago, Ill., assignor to Westinghouse Electric Elevator Company, Chicago, Ill., a corporation of Illinois

Application December 20, 1934, Serial No. 758,434

6 Claims. (Cl. 198—16)

My invention relates to moving stairways in which the moving steps are operated by endless gear chains disposed on a plurality of sprocket wheels, and more particularly, to the control systems and safety devices for such stairways.

One object of my invention is to provide for stopping a stairway when a break occurs in its driving means.

Another object of my invention is to provide one means for stopping the driving means of the moving stairway and, after a predetermined interval, applying a second or additional means for preventing movement of the stairway until the driving means is again started in a normal manner.

A further object of my invention is to provide for stopping the stairway motor and the stairway, without imposing an undue strain upon the motor or upon the motor worm shaft.

It is also an object of my invention to provide for so operating a stairway that it will be stopped promptly and automatically when breakage of any part, or any dangerous condition arises in connection with the stairway.

Other objects of the invention will be apparent from the following description, taken in conjunction with the accompanying drawings, in which:

Figure 1 is a view in side elevation of the main parts of a moving stairway embodying my invention;

Fig. 2 is a top plan view of the motive parts of the stairway shown in Fig. 1;

Fig. 3 is a view in end elevation of the sprocket wheels, and the supporting means therefor, shown at the lower landing in Figs. 1 and 2;

Fig. 4 is an enlarged view of the safety switch and a portion of its operating mechanism associated with the drive chain in Figs 1 and 2; and,

Fig. 5 is a diagrammatic representation of the electrical control system for controlling the motor which drives the stairway.

The right-hand side of the diagram shown in Fig. 5 is drawn in what is known as the straight line style for electrical wiring, and the left-hand portion provides a key to the mechanical relation between the coils and the contact members in the right-hand side of the drawings, in order that the reader may readily determine the location of any relay in the right-hand side of the diagram, the number of its contact members, and the points at which the contact members are disposed in the system.

Referring more particularly to the drawings,

I have illustrated a moving stairway comprising an endless series of movable steps 1 disposed to be operated along their tracks 2 by a pair of gear chains 3 and 4 between an upper landing 5 and a lower landing 6. The gear chains are supported at the upper landing by a pair of driving sprocket wheels 7 and 8 and at the lower landing by a pair of tensioning sprocket wheels 9 and 10. A suitable truss or frame 11 of structural steel is provided for supporting the stairway between its upper landing and its lower landing.

The driving sprocket wheels 7 and 8 are positively connected by a large torque tube 13 and are mounted by suitable roller bearings or other means (not shown) upon a supporting shaft 14, the outer ends of which are supported by a pair of suitable standards 15 and 16.

A motor 18 is provided for driving the sprocket wheels 7 and 8 through a driving shaft 19, a reduction gear 20, a driving pinion 21, a driving chain 22 and a chain sprocket wheel 23 which is securely attached to the driving sprocket wheel 7 by a plurality of bolts or rivets (not shown).

The lower sprocket wheels 9 and 10 are connected by a sleeve or torque tube 25 provided with suitable flanges 26 and 27 bolted to suitable cooperating flanges 28 and 29 upon the inner portions of the sprocket wheels by a plurality of bolts 30. As shown, the sleeve 25 firmly connects the sprocket wheels at the lower landing and causes them to rotate in unison with each other.

In order to keep the gear chains under such predetermined tension as may be desirable, the sprocket wheels at the lower landing are mounted upon a pivotal carriage comprising a shaft 31 and a pair of end trucks 32 and 33. The shaft passes through the sleeve 25 and the axes of the gear wheels 9 and 10 and is supported at its ends by the trucks 32 and 33. A set screw 34 is disposed in the upper portion of each of the trucks 32 and 33 in position to screw into engagement with the end portions of the shaft 31 to prevent rotation of the shaft and also to secure the ends of the shaft in the trucks.

The truck 32 comprises a heavy casting or frame 37, a pair of supporting wheels 38 and 39, and a guiding wheel 40. The wheels 38 and 39 are mounted in slots in the underside of the casting in a plane parallel to the plane of the sprocket wheel 10. The wheel 40 is disposed between the wheels 38 and 39 and pivotally secured to the underside of the casting 37 in a

horizontal plane. A track rail 42 is located underneath the wheels 38 and 39 to support the truck and a guide rail 43 is disposed on the outside of the guide wheel 40 to limit sidewise movement of the truck. The guide rail 43 may be welded to the track 42 to unite the two in a rigid angle iron track and guide.

The truck 33 is similar to the truck 32 and comprises a heavy cast frame 46, a pair of supporting wheels 48 and 49 and a guide wheel 50. A track rail 52 and a guide rail 53 are provided for the wheels 48, 49 and 50. The track rails 42 and 52 and the guide rails 43 and 53 may be suitably welded to the associated angle iron members 47 comprising a portion of the frame or truss 11.

In view of the description of the carriage for the lower sprocket wheels, it will be seen that the carriage can move back and forth on the wheels 38 and 39 and 48 and 49, and can turn in a pivotal manner by reason of the horizontally disposed guiding wheels 40 and 50.

A tensioning means 54 is provided for each truck to keep the gear chains under such tension as may be desired. Each tension device 54 comprises a rod 55 pivotally connected to the truck 32 in position to extend rearwardly through the frame member 47 and a compression spring 56 concentrically disposed on that portion of the rod 55 extending rearwardly beyond the frame member 47.

This spring may be held under such compression as is desired by means of a stop member 57 and a pair of nuts 58 also concentrically mounted upon the rod 55. The nuts 58 are so disposed on the screw-threaded end of the rod 55 that the position of the stop member 57 and, therefore, the amount of compression on the spring 56, may be adjusted to any desired amount by rotating the nuts. The truck 33 is provided with a tensioning means that is similar to the tensioning means described for the truck 32. Therefore, it will be obvious that the tension on the gear chains may be adjusted to any desirable amount by adjusting the nuts 58 on the rods 55.

A safety switch 60 is mounted adjacent to each of the tensioning devices 54. The switch comprises a frame 61 supported by an angle iron 62 on a portion of the truss frame 11, as shown in Figs. 1, 2 and 4. A contact member 63 is suitably mounted in the frame 61 in position to be engaged by a cooperating contact member 63a. The contact member 63a is biased away from the contact member 63 by a compression spring 65.

A trigger 66 is provided for normally engaging a projection 64 on the spring contact member 63a and thereby hold it in engagement with the stationary contact member 63. The trigger is pivotally mounted in the frame 61 with its lower end extending downwardly into a position between a pair of projections on the stop member 57. If the stop member 57 is moved either forwardly or backwardly beyond a predetermined distance by the operation of the tensioning devices 54, the projections will move the trigger from the projection 64 and thereby release the contact member 63a from the contact member 63, thus opening the switch 60.

Hence, it will be obvious that if either of the trucks 32 or 33 moves either forwardly or backwardly beyond a predetermined distance because of the stretching or breaking of one or both chains or because of the steps catching on a projection, the corresponding safety switch 60 will

be opened. Also, it will be obvious that, by reason of the projection 64 on the contact member 63a, the trigger cannot again close the switch until the contact member 63a is raised by hand into engagement with the stationary contact member. Hence a temporary movement of either of the trucks beyond a predetermined distance will cause its switch 60 to open and remain open until it is manually reset.

A motor brake 70 is mounted upon the motor shaft 19 for the purpose of stopping the motor and the stairway when desired. Any suitable brake may be employed, such as the spring-applied electromagnetically released type of brake usually associated with electric motors. When the electromagnetic coil 71 of the brake 70 is deenergized, the brake will be applied to the motor shaft to prevent rotation of the motor and the consequent operation of the driving chain 22 and the stairway steps.

The motor brake 70 is a service brake for positively stopping and holding the stairway against movement when the attendant desires to stop the operation of the stairway. The motor brake is also made responsive to the various safety devices associated with the stairway for positively stopping and holding the stairway when any dangerous condition arises except that of a break in the drive chain.

An emergency brake 73 is provided for positively stopping and holding the stairway in case of breakage of the driving chain 22.

Any suitable emergency brake may be used, but the one illustrated is a brake of the snubber type comprising a band 74 disposed around a brake drum 75 firmly secured to the torque tube 13. The ends of the band 74 are pivotally secured to a brake lever 76 pivotally mounted in a brake support 77 securely attached to a cross-member 78 on the truss frame 11. A plurality of weights 79 are disposed on the outer end of the brake arm 76 to bias it to its brake-applying position. The number of weights may be adjusted as desired to vary the braking effect.

The means for releasing the emergency brake 45 is an electromagnet 81 which is securely fastened to the truss frame 11 at a point above the outer end of the brake lever. The armature 82 of the electromagnet is so connected by a rod 83 to the outer end of the brake lever 76 that energization of the electromagnet 81 will draw the armature 82 upwardly and thereby pull the rod 83 and the brake lever 76 upwardly against the downward pull of the weight 79 and thus release the brake band 74 from the brake drum 75. When the electromagnet is deenergized, the upward pull upon the rod 83 ceases thereby permitting the weight 79 to exert such a downward pull on the brake lever 76 as to cause the brake band 74 to effectively apply a braking pressure to the brake drum 75 and thereby prevent any further movement of the stairway.

Normally, it would be necessary to provide for the application of the emergency brake only in the event of the breakage of the driving chain, but inasmuch as the emergency brake is held in its released condition by the electromagnet 81, it will be more economical to deenergize the magnet when the stairway is not running. This will, of course, apply the emergency brake 70 to its brake drum. Therefore, I have arranged to deenergize the emergency brake, whenever the stairway is stopped by the application of the motor brake. In view of this, I have provided for deenergizing the emergency brake 75.

within four or five seconds after the motor brake is applied. This causes the emergency brake to become fully effective several seconds after the motor brake is made effective, and permits a saving in the current which would otherwise be necessary to maintain the emergency brake in a released condition at all times except upon breakage of the driving chain. The means for effecting the delay in the application 10 of the emergency brake will be hereinafter described.

It is, of course, advisable to apply the emergency brake instantly in the event of breakage of the driving chain because if the driving chain is broken, the brake 71 cannot then prevent movement of the stairway, even though that brake is promptly applied to prevent rotation of the motor shaft.

In order to make the application of the emergency brake responsive to breakage of the driving connections, I have provided a safety switch 86 for operation by a shoe 87 disposed to ride upon the upper surface of the driving chain. The shoe is mounted upon a rod 84 connected 25 to the outer end of a lever 85 for operating the safety switch 86. The safety switch 86 is constructed in the same manner as the safety switch 60, shown in Fig. 4 and is so connected electrically to the electromagnetic coil 81 of the emergency brake that if the driving chain breaks, the shoe 87 will, by reason of its weight, drop downwardly and thus move the rod 84 and the lever 85 downwardly to open the switch 86 and apply the emergency brake to effect the 30 stopping of the stairway.

As another safety measure, a safety governor 90 is disposed upon one end of the motor shaft 19. The governor comprises a collar 140, a pair of governor weights 141, and a spring 142. The 35 collar is slidably mounted on the shaft 19. The weights are pivotally mounted on the collar and have their inner ends disposed in slots in the shaft. The spring is so disposed in compression between the outer end of the shaft and the outer end of the collar as to bias the weights to an inner position along the shaft when the motor is not running. When the motor is in 40 operation it will rotate the weights and the centrifugal force generated thereby will move them outwardly and hence move the collar along the shaft in accordance with the speed of the motor.

An underspeed switch 114 is so disposed as to be closed by the movement of the collar 140 when the motor accelerates to a predetermined speed. This switch stays closed as long as the motor remains above that predetermined speed. An overspeed switch 113 is so disposed as to be opened when the motor goes above a predetermined speed. The underspeed switch prevents the closing of a self-holding circuit for the motor after it starts until it reaches a predetermined speed. The overspeed switch opens to stop the motor when it exceeds a predetermined safe speed. The overspeed switch is constructed upon the same principle as the switch 60 so that after being opened it cannot be closed without manual resetting, thereby calling the attention of the attendant to the condition of the stairway before it can be restarted.

Referring now to the schematic diagram of the motor and control system shown in Fig. 5, the main switches and relays in the control system are designated as follows:

A=Current overload relay.

B=Phase protective relay.

C=Time control relay for controlling accelerating relay.

D=Brake timing relay for controlling emergency brake relay.

E=Accelerating relay.

F=Up direction switch.

G=Down direction switch.

H=Up direction relay.

J=Line switch.

K=Down direction relay.

M=Emergency brake coil.

O=Running relay.

P=Emergency brake relay coil.

The contact members of the relays are designated by the same reference letters as the relays with added numerals to indicate the specific contact members.

The driving motor 18 comprises a squirrel cage 20 rotor 95, (Fig. 5) and field windings 96, 97 and 98. A plurality of resistors 99, 100 and 101 are provided for controlling the speed of the motor. The supply conductors L1, L2 and L3 to the motor field windings may be connected to a suitable source of supply by a switch 102.

The control system, as shown below the motor diagram, is preferably designed for direct current operation, and its supply conductors L4 and L5 are shown as adapted to be connected to the supply conductors L1, L2 and L3 by a suitable rectifier 103, preferably of the copper oxide type. Inasmuch as rectifiers of this type are old and well known, no further detailed description thereof will be given.

The energization of the motor 18 is controlled by the line switch J and its direction of operation is controlled by an up direction relay H and a down direction relay K. The line switch J and the direction relays H and K are in turn controlled by an up direction switch F and a down direction switch G.

The stairway may be started for up operation by pressing a push button 105 at the upper landing, or a pushbutton 106 at the lower landing, or a pushbutton 107 in the motor compartment to energize the up direction switch F. The stairway may be started for down operation by pressing a down pushbutton 108 at the upper terminal, or a down pushbutton 109 at the lower terminal, or a down pushbutton 110 in the motor compartment to energize the down direction switch F.

The speed of the motor is controlled by the accelerating relay E for connecting and disconnecting the resistors 99, 100 and 101 in the circuit for the field windings of the motor. The time control relay C delays the operation of the accelerating relay E for a predetermined period after the motor is first energized, so that the resistors 99, 100 and 101 will not be disconnected from the motor until the motor starts.

Although any timing relay may be used I have indicated one provided with the usual energizing coil and a neutralizing coil CN. The neutralizing coil is connected across the supply conductors L4 and L5 for continuous energization and thereby delays the operation of the relay when its main energizing coil is deenergized. The time control relay C is controlled, in turn, by the line switch J, so that the accelerating relay is energized a predetermined time after the line switch is energized and is deenergized immediately when the line switch is deenergized.

The electromagnet coil 71 on the motor brake

10 is controlled by the line switch J and the direction relays H or K, in such manner that the motor brake coil is energized to release the motor brake as soon as the line switch and one of the 5 direction relays are energized to start the stairway and to apply the motor brake whenever the line switch and the associated direction relay are deenergized to stop the stairway.

The stairway may be stopped by pressing either 10 a stop button 116 at the upper landing, a stop button 117 at the lower landing, an inching button 118 in the motor compartment, or an inching button 119 located near the sprocket wheels at the lower landing. When one of these buttons 15 is pressed, it deenergizes the line switch J and the associated direction relay to effect the stopping of the stairway.

The coil M of the emergency brake is so controlled that it is energized to immediately release 20 the emergency brake upon the starting of the stairway but is not deenergized until after the expiration of a predetermined time after the stairway stops. The coil is controlled directly by the emergency brake relay P which is controlled 25 by the brake timing relay D which is controlled by either the up direction switch F or the down direction switch G. The brake timing relay is provided with a neutralizing coil DN connected across the supply conductors L4 and 30 L5 for constant energization so that the relay D will not operate after being deenergized until the expiration of a predetermined period of time. The running relay O is also energized by the up direction switch F or the down direction 35 switch G and operates to provide a holding circuit for the timing relay D while the stairway is in operation.

As stated above, when the stairway makes a 40 normal stop, the emergency brake is applied after the expiration of a predetermined period of time after the stairway motor has been disconnected from its supply conductors. The circuit for the coil of the emergency brake is also controlled by normally closed contact members 121 on the 45 switch 86 controlled by the safety shoe 87. If the chain breaks, the shoe will drop downwardly by reason of gravity, thus opening the contact members 121 and thus immediately applying the emergency brake to stop the stairway upon 50 breakage of the chain.

In order to protect the motor and the control system in their operation, the current overload relay A has its coils included in the supply conductors L1 and L3, the phase protective relay 55 B has its coils connected across the alternating current supply conductors and a plurality of fuses 122, 123 and 124 are connected in circuit with the supply conductors leading to the rectifier 103.

60 If the current on the motor 18 becomes excessive, the overload relay A will open its contact members A1 in the circuit for the line switch J, and thereby deenergize that switch to stop the motor and apply the motor brake. Upon phase 65 reversal or failure, the phase protective relay B will become effective to open the contact members B1 in the circuit of the line switch J to stop the motor and the stairway. Under other conditions, if the fuses 122, 123 and 124 are blown by an excessive load, the rectifier 103 and consequently the control circuit will be deenergized, thereby deenergizing the line switch J and effecting the stopping of the motor and the stairway.

A control switch 129 is disposed in the circuit 75 of the line switch J. This switch may be located

at any desirable point, for instance, in the motor compartment, where it may be opened to prevent operation of the stairway while it is being cleaned, inspected or repaired.

A plurality of resistors R1, R2, R3, R4 and R5 5 are included, respectively, in series with the neutralizing coils CN and DN of the relays C and D, the brake coil 11, the coils of relays H, J and K, the emergency brake coil M and the coils of 10 relays O and D to decrease the current consumption and thereby prevent overheating of the coils and economize on the current taken by the rectifier.

In order to provide for dissipating energy when the circuits are interrupted, I have provided a 15 resistor R6 in parallel with the motor brake coil 112, a resistor R7 in parallel with the emergency brake coil M, and a resistor R8 in parallel with the coil of the time control relay C.

Operation of stairway

20

The stairway may be operated as follows: It will be assumed that an attendant presses the up button 105 at the upper landing to start the stairway for up operation. It will be necessary 25 for the attendant to keep this button in closed position until the stairway starts and accelerates to such a speed. The pressing of the button 105 energizes the up direction switch F by a circuit extending from supply conductor L4 through the 30 contact members of button 105, coil F and the contact members G1 to the supply conductor L5.

The energization of the up direction switch F opens its contact members F1 and closes its contact members F2 and F3. The opening of 35 the contact members F1 electrically interlocks the down direction switch G to prevent its energization while the up direction switch F is energized. The closing of the contact members F2 prepares but does not complete the circuits for 40 the line switch J and the up direction relay H. The closing of the contact members F3 energizes the running relay O and the brake timing relay D by a circuit extending from the supply conductor L4 through the contact members E4 45 thence in parallel through the coils O and D and thence through the contact members F3, conductor 130 and the contact members B1, 113, A1, 63, switch 129, the contact members of push buttons 116, 117, 118 and 119 and the contact 50 members 121 to the supply conductor L5.

The energization of the running relay O closes its contact members O1 in the circuit of the brake timing relay D and thereby provides a self-holding circuit for the relay D.

55

The energization of the brake timing relay D closes its contact members D1 and thereby energizes the emergency brake relay P by a circuit extending from the supply conductor L4 through the contact members E4, conductor 131, the contact members D1 and the coil of relay P to the supply conductor L5.

The energization of the emergency brake relay P closes its contact members P1 thereby energizing the emergency brake coil M by a circuit 65 extending from the supply conductor L4 through the contact members P1, M2, the coil M and the contact members 121 to the supply conductor L5. The energization of the emergency brake M of the electromagnet 81 pulls upwardly on the rod 70 83 and thereby lifts the brake arm 76 to release the brake band 74 from the drum 75 and thus prepare the stairway for operation.

The energization of the emergency brake coil 75 M also opens its contact members M2 in its own

75

circuit and thereby inserts the resistor R4 in series with the coil M, thus reducing the current consumption of the coil and preventing it from overheating while it is energized during continuous operation of the stairway.

- 5 The energization of the emergency brake also closes its contact members M1 thereby energizing the up direction relay H and the line switch J by a circuit extending from the supply conductor L4 through the contact members F2, the coils of relay H and line switch J, the contact members M1, B1, 113, A1 and 63, switch 129, contact members of push buttons 116, 117, 118 and 119 and the contact members 121 to the supply conductor L5.

10 The energization of the line switch J closes its contact members J1, J2 and J3 and opens its contact members J4. The closing of the contact members J1 and J2 connects the driving motor 18 to the supply conductors L1, L2 and L3 in preparation for starting the motor. The closing of the contact members J3 prepares for energization the circuit of the machine brake coil 71. The opening of the contact members J4 opens the circuit of the time control relay C, but that relay does not yet operate because of the effect of its neutralizing coil CN.

- 15 The energization of the up direction relay H closes its contact members H1, H2, H3 and H4. 20 The closing of the contact members H1 and H2 completes the circuit for energizing the motor 18 to operate the stairway in the up direction. One branch of the circuit extends from the switch 102 through the supply conductor L1, the contact members J1, coil A, coil 96, and resistor 99 to the junction point 132; the second branch of the circuit extends from the switch 102, conductor L2, contact members H1, coil 97 and resistor 100 to the junction point 132; and the 25 third branch extends from the switch 102 through the conductor L3, contact members J2 and H2, coil A, coil 98 and resistor 101 to the junction point 132. At the same time the closing of the contact members H3 completes the 30 circuit for energizing the machine brake coil 71 to release the brake 70 by a circuit extending from the supply conductor L4 through the contact members H3 and E3, coil 71 and contact members J3 to the supply conductor L5. The 35 energization of the motor 18 and the brake coil 71 starts the motor and releases the machine brake so that the stairway now starts in operation for the up direction. The closing of the contact members H4 closes one gap in a self-holding circuit for the relay H and the switch J.

40 Referring again to the deenergization of the time control relay C, by the opening of the contact members J4, it will be assumed that several seconds have passed and that this relay now responds to its deenergization and closes its contact members C1, thereby energizing the accelerating relay E by a circuit extending from the supply conductor L4 through the contact members H3, conductor 133, coil E and the contact members C1 to the supply conductor L5.

45 Energization of the relay E closes its contact members E1, E2 and opens its contact members E3 and E4. The closing of the contact members E1 and E2 short circuits the resistors 99, 100 and 101 connected in the field circuit of the motor 18 and thereby causes the motor to accelerate and operate the stairway at full speed.

50 The opening of the contact members E3 inserts the resistor R2 in the circuit of the motor brake coil 71, thereby cutting down the current

55 supply to that coil and preventing its overheating while the brake is being held in its released position and also reducing the load upon the rectifier 103. The opening of the contact members E4 inserts the resistor R5 in the circuit for the relays O, D and P, thereby cutting down the current through these coils to prevent their over-heating in operation and also to reduce the load on the rectifier 103.

60 As the driving motor 18 accelerates to full speed operation, the safety governor 90 operates to close its underspeed contact members 114, thereby completing a self-holding circuit for the up direction relay H and the line switch J. This self-holding circuit extends from the supply 65 conductor L4 through the contact members 114 of the governor 90, resistor R3 and the contact members H4 to the coils H and J.

65 As soon as this point is reached in the operation of the stairway, the attendant may release the up direction button 105, thereby deenergizing the up direction switch F to close its contact members F1 and open its contact members F2 and F3. The closing of the contact members F1 has no effect, but the opening of the contact members F2 compels the current to the relay H and the line switch J to follow through the self-holding circuit completed by the closing of the contact members 114 of the safety governor 90, thereby inserting the resistor R3 in this circuit. 70 The resistor R3 cuts down the current to the coils H and J, thereby preventing their over-heating during continued energization and also reduces the load upon the rectifier 103.

75 By reason of the operation just described, it will be seen that the car attendant in starting the stairway into operation presses one of the starting push buttons and holds it in its depressed position until the stairway accelerates to such predetermined speed that the safety governor 90 completes the self-holding circuit for the direction relay and line switch and that the attendant may then release the pushbutton and the stairway will continue in operation until it is stopped by operation of one of the stopping buttons or by 80 operation of one of the safety devices.

85 It will now be assumed that the attendant, desiring to stop the operation of the stairway, presses the down stop button 116 at the upper landing. This operation opens the circuit for 50 the up direction relay H and the line switch J, the running relay O and the emergency brake timing relay D.

90 The deenergization of the up direction relay H opens its contact members H1, H2, H3 and H4. 55 The opening of the contact members H1 and H2 deenergizes the driving motor 18 and stops it. The opening of the contact members H3 deenergizes the machine brake coil 71, thereby applying the brake 70 to stop the operation of 60 the driving motor and the stairway. The opening of the contact members H4 opens the self-holding circuit of the motor H, but this has no effect as the relay H has already been deenergized by the opening of the contact members of 65 the stop button 116.

95 The deenergization of the line switch J also opens its contact members J1, J2 and J3 in the circuits for the motor 18 and the machine brake coil 71.

100 The deenergization of the line switch J also closes its contact members J4, thereby energizing the time control relay C to open its contact members C1, thereby deenergizing accelerating relay E to close its contact members E1 and E2 75

to reinsert the resistors 99, 100 and 101 in the motor circuit, and to close its contact members E3 to short circuit the resistor R2 in the circuit for the motor brake coil 71 in preparing 5 the motor circuit and the control circuit for restarting.

The deenergization of the relay O opens its contact members O1, thereby deenergizing the brake timing relay D. However, because of the 10 neutralizing coil DN on the brake timing relay D, this relay delays opening its contact members D1 for a predetermined period (in this case approximately 5 or 6 seconds). The delayed deenergization of the relay P causes its 15 contact members to now open and deenergize the emergency brake coil M, thereby applying the emergency brake to the driving sprocket wheels of the stairway approximately five seconds after the setting of the machine brake.

20 As stated above, the setting of the emergency brake occurs every time the stairway stops, but does not take place until after the expiration of a predetermined period of time such as five or six seconds after the machine brake has set to 25 stop the stairway. Inasmuch as either brake is sufficiently strong to stop the stairway, it will be understood that if both brakes were set simultaneously the braking action on the stairway would be too severe. Therefore, the provision of the timed delay emergency brake provides not only a flexible and effective braking 30 operation for the stairway, but also provides an absolutely safe braking system.

By following the circuit for the up direction 35 relay H and the line switch J, which control the operation of the motor and the motor brake, as well as the delay operation of the emergency brake, it will be observed that this circuit includes the contact members M1 of the emergency brake, the contact members B1 of the phase protecting relay B, the contact members 113 of the safety governor 90, the contact members A1 of the overload relay, the contact members 63 of the stop chain switches 60 and the contact members 121 of the driving chain safety switch 86. Inasmuch as these contact members are normally closed during the operation of the stairway, it will be seen that if the emergency 40 brake is deenergized, or the phase protective relay is operated, or the safety governor 90 operates at high speed, or the overload relay A is operated, or either of the stop chain switches 60 is operated by stretching, breaking or catching of the step chains, or the contact members 55 121 are opened by the breaking of the drive chain, the line switch J will be immediately deenergized to stop the stairway.

It will be assumed now that the stairway is again placed in operation for the up direction 60 as previously described and that while it is so operating at full speed, the driving chain breaks. The breaking of the driving chain will permit the weighted shoe 87 to move downwardly and thereby operate the rod 84 and the lever 85 to 65 open the contact members 121 of the switch 86. The opening of the contact members 121 immediately opens the circuit of the emergency brake coil M to instantly apply the emergency 70 brake to the driving sprocket wheels of the moving stairway, thereby making an emergency stop of the stairway. At the same time the opening of the contact members 121 deenergizes the up direction relay H and the line switch J to immediately stop the motor 18 and apply the machine 75 brake on the motor shaft, as previously

described. Hence it is seen that the provision of the emergency brake and its control system provides an additional safeguard for the operation of the stairway.

It will also be apparent that the provision of the machine brake and the delayed operation of the emergency brake, as well as the low speed contact members on the safety governor 90 provides a system whereby the stairway may be "inched" along by the attendants when it is desired to make repairs or slowly move the steps to some predetermined point. For instance, if one of the starting buttons is held in closed position to start the stairway and one of the "inching" buttons 118 or 119 or one of the stop buttons 116 or 117 is pressed before the stairway comes up to the degree of speed whereby the governor contact members 114 are closed, the stairway motor will be started at slow speed and stopped after it goes only a very short 20 distance, and that by immediately releasing the "inching" button or the stop button before the emergency brake is applied, the stairway may be again started and stopped at slow speed. It will be apparent that the "inching" operation 25 may be kept up by pressing one of the inching buttons or one of the stop buttons before the motor accelerates to a position whereby the low speed governor contact closes, and by again releasing the inching button or the stop button 30 before the expiration of the time when the emergency brake sets, until the stairway steps are moved to the point desired or until the slow speed inspection is completed.

By reason of the foregoing description, it will 35 be seen that I have provided for the operation of a moving stairway under all conditions in a safe and simple manner.

Although I have illustrated and described only one specific embodiment of my invention, it is 40 to be understood that many modifications thereof and changes therein may be made without departing from the spirit and scope thereof.

I claim as my invention:

1. A machine, a drive motor, a control system 45 for effecting energization and deenergization of the motor, a shaft for the driving motor, means connecting the shaft to the machine whereby movement of the one will be transmitted to the other, a machine brake for the shaft, means responsive to deenergization of the motor for applying the machine brake to the shaft, an emergency brake for the machine, means responsive to operation of the control system to deenergize the motor for applying the emergency 50 brake to the machine, and means responsive to operation of the control system for delaying the application of the emergency brake to the machine for a predetermined period of time after the application of the motor brake. 60

2. In a moving stairway having an endless series of steps, a gear chain for operating the steps, a driving sprocket wheel for operating the gear chain, a driving motor, a control system for energizing and deenergizing the motor, a 65 shaft for the driving motor, a machine brake for the shaft, means connecting the driving shaft to the driving sprocket wheel whereby operation of the one causes operation of the other, an emergency brake for controlling the driving 70 sprocket, means responsive to operation of the control system to deenergize the motor for applying the machine brake to the shaft to stop the motor and the stairway for applying the emergency brake to stop the driving sprocket 75

wheel and for delaying the application of the emergency brake for a predetermined period of time after deenergization of the driving motor.

3. In a moving stairway having an endless series of steps, a pair of gear chains for operating the steps, a pair of driving sprocket wheels for operating the gear chains, a driving motor, a control system for effecting energization and deenergization of the driving motor, means connecting the driving motor and the driving sprocket wheels whereby rotation of the one effects rotation of the other, a machine brake for stopping the driving motor, an emergency brake for the driving sprocket wheels, means responsive to operation of the control system to deenergize the motor for applying the machine brake to stop the motor and the stairway, for applying the emergency brake to the driving sprockets and for delaying the application of the emergency brake for a predetermined period after the deenergization of the driving motor.

4. In a moving stairway having an endless series of steps, a pair of gear chains for operating the steps, a pair of sprocket wheels for operating the gear chains, a driving motor, means connecting the driving motor to the driving sprocket wheels whereby rotation of the one effects rotation of the other, a machine brake for controlling the motor and the stairway, an emergency brake for controlling the sprocket wheels and the stairway, a plurality of circuits for the motor, the machine brake and the emergency brake, control relays for controlling the circuits to energize and deenergize the motor, a relay responsive to operation of the control relays for effecting application of the machine brake to stop the motor and the stairway, a re-

lay for controlling the emergency brake, and a time delay relay responsive to operation of the control system in deenergizing the motor for controlling the emergency brake relay to effect application of the emergency brake to the driving sprocket wheels only upon the expiration of a predetermined period of time after the operation of the control system to deenergize the driving motor.

5. In a moving stairway having an endless series of steps, a gear chain for operating the steps, a driving sprocket wheel for operating the gear chain, a driving motor, means connecting the driving motor and the driving sprocket wheel whereby rotation of the one effects rotation of the other, a machine brake for the driving motor, an emergency brake for the driving sprocket wheel, a control system for the motor, and means responsive to operation of the control system to start the motor for releasing both brakes and means responsive to the operation of the emergency brake for preventing operation of the control system to energize the driving motor until the emergency brake is released.

6. In a moving stairway having an endless series of steps, a motor for driving the steps, a brake for controlling the operation of the steps, a control system for the motor, a control device, means responsive to operation of the control device for effecting the release of the brake and for preparing the control system to effect the starting of the motor, and means responsive to the release of the brake for causing the prepared control system to effect the starting of the motor.

EDGAR M. BOUTON.
